EDGAR H. BARBÉ, OF LOS ANGELES, CALIFORNIA, ASSIGNOR TO ROLLODOR MANUFACTURING COMPANY, A PARTNERSHIP COMPOSED OF AMALIA EARLES AND EDGAR H. BARBE, BOTH OF LOS ANGELES, CALIFORNIA

MOBILE ASH TRAY

Application filed September 5, 1931. Serial No. 561,859.

This invention relates to a self righting mobile standard adapted to support an ash tray. It pertains more especially to the running gear to provide a housing enclosing the elements and capable of simulating a body whose form is revolute. Thus, the running gear may include wheels merging in a configuration of substantially spherical form so as to have the ornate general appearance of a sphere. However the running gear may simulate any other body having a surface of revolution generated by a line.

It is an object of this invention to provide a self righting mobile standard the running gear being a revolute and formed of three segments side by side, with wheels having rims at the surface of the revolute and located at the junctures of the segments. The medial segment forms an overweighted body with an outstanding standard. Other objects of this invention are to provide a self righting mobile standard having details of structure contributing to simplicity of construction, ornateness in appearance, ease of assembly and disassembly and economy of manufacture.

These objects are accomplished by means of the embodiment of my invention illustrated in the accompanying drawing, in which:—

Fig. 1 is an elevation with a portion of the running gear broken out and shown in section; Fig. 2 is an elevation at right angles to Fig. 1 with a portion of the running gear shown in section.

Referring more particularly to the drawing, the running gear is shown simulating a sphere. The sphere is divided into three segments. The middle segment 3 is symmetrical in form and at its ends has outwarded flanges 4. There is a bore at the middle portion of the section and surrounding the bore is a collar 5. A weight 6 of segmental form fills the lower part of the medial section and overhangs the flanges. This weight is secured to the shell of section 3 by means of screws 7. A boss 8 extends from the chordal side of the weight 6 and has a tapped bore forming a socket for the shank 50 of a standard. Extending through the boss

and transverse to the socket bore is a bore for a shaft 9 which is fixed in position upon the weight by a pin 10 extending through the boss and shaft. The shaft has annular grooves 11 at its outer ends.

Mounted upon the ends of the shaft are hub sleeves 12 having disk wheels 13, secured thereon by lateral beads 14. The wheels are rotatably secured in position upon the shaft by pins 15 passed through holes in the sleeves and lying in grooves 12. The sleeves are tapped at their outer ends. End shells 16 complete the sphere and serve as hub caps. Fixed to the shells 16 at their centers are threaded posts 17 engaged with the tapped bores of hub sleeves 12 thereby holding the end segments in position. The wheels 13 have rims 18.

The shank 19 of the standard is passed through collar 5 and secured in the socket by being screwed into position and carries an ash tray 20 at the top. This ash tray may be of any suitable form and is shown with a sleeve 21 for reception of a lighter 22.

It will be noted that the medial segment is overweighted so as to maintain the standard upright. The rims 18 of the wheels are of greater diameter than the sphere so that the base is supported on the wheels and the structure may be rolled about. It is obvious that any shell which is a revolute may be used to produce an ornate appearance.

What I claim is:—

1. A mobile self righting standard structure comprising a base, said base being revolute, hollow and divided into three segments disposed side by side along the axis thereof, a weight detachably secured to the medial segment with its center of gravity on one side of the axis thereof and having a tapped socket on the opposite side, a standard threaded into said socket, an axially disposed shaft secured to said weight and extending from the ends of said medial segment, hub sleeves detachably and rotatably secured on the ends of said shaft, and wheels on said hub sleeves extending between adjacent segments with rims overlying the junctures of said segments, the end segments being hollow and having threaded posts secured in said sleeves.

2. A mobile self righting standard structure comprising a hollow base, said base being substantially spherical and divided normal to a diameter into three segments, the 5 medial segment being symmetrical and having an axially disposed shaft extending through and overhanging its ends, disk ground wheels having sleeve hubs journalled on said shaft, means detachably securing said wheels in position on said shaft, a weight in and secured to said medial segment having its center of gravity eccentric to the axis thereof, and a standard outstanding from said medial segment opposite to and secured 10 to said weight, the end segments having threaded posts for attachment of the end segments to said hub sleeves and thereby constituting hub caps, the peripheries of said 15 wheels being of greater diameter than the sphere.

3. A mobile self righting standard structure comprising a hollow base, said base being substantially spherical and divided normal to a diameter in three segments, the 25 medial segment being symmetrical, a weight disposed in and detachably secured to said medial segment having its center of gravity eccentric to the axis thereof, a tapped boss on said weight, a standard threaded into said 30 boss and outstanding from said medial segment opposite said weight, a bore extending through said weight a shaft detachably secured in said bore and having ends overhanging the ends of said medial segment, disk 35 wheels having hub sleeves rotatably mounted on the ends of said shaft, the end segments having posts for engaging said sleeves and thereby constituting hub caps, and rims on 40 said wheels overlying the junctures of said segments, said rims being of greater diameter than the sphere.

4. A mobile self righting standard structure comprising a hollow base, said base being substantially spherical and divided normal to a diameter into three segments, the medial segment being symmetrical, a weight in said medial segment having its center of gravity eccentric to the axis, a shaft extending 45 through said weight and outward from the ends of said medial segment, with annular grooves on the ends of said shaft, disk ground wheels having hub sleeves journalled on the ends of said shaft, cotter pins passed 50 through said hub sleeves and lying in said grooves whereby to secure said wheels in position on the ends of said shaft, the ends of said sleeves being tapped, a standard outstanding from said medial segment opposite 55 to the center of gravity of said weight, the end segments having threaded posts engaged with the tapped ends of said sleeves for attachment of the end segments and constituting hub caps, and rims on said wheels overlying 60 the junctures of said segments, said 65

rims being of greater diameter than the sphere.

In witness that I claim the foregoing I have hereunto subscribed my name this 29th 70 day of August, 1931.

EDGAR H. BARBÉ.
